UNITED STATES PATENT OFFICE.

JAMES DOUGLAS MACMAHON, OF NIAGARA FALLS, NEW YORK, ASSIGNOR TO THE MATHIESON ALKALI WORKS, OF NEW YORK, N. Y., A CORPORATION OF VIRGINIA.

CLARIFICATION OF BLEACH LIQUORS.

No Drawing.

Application filed March 10, 1925. Serial No. 14,576.

This invention relates to the clarification of calcium hypochlorite liquors such as are used in the pulp and paper industries for bleaching. Such bleach liquors are commonly made either by dissolving bleaching powder in water or by chlorinating suspensions of lime in water. Commercial bleaching powder always contains some excess free lime, and, when the bleaching powder is dissolved, this free lime, excepting the small amount dissolved, is suspended in the solution. When the bleach liquor is prepared by chlorinating a suspension of lime, an excess of lime is used to produce a stable liquor and to facilitate control of the chlorinating operation. The lime employed may also contain other associated insoluble mineral matter, and where bleaching powder is used insoluble impurities such as calcium carbonate may also be present. The result is that the bleach liquors, as commonly prepared, always contain some suspended lime in varying degrees of sub-division and frequently contain other insoluble impurities.

In the pulp and paper industry it has been found that such suspended mineral matter, and particularly free undissolved lime, is seriously detrimental to the effective use of the bleach liquors. To overcome this difficulty it has been customary to subject the bleach liquor, after solution of the bleaching powder or chlorination of the lime suspension, to long periods of settling, followed by decantation of the supernatant liquor from the precipitated residue. Not only have such methods involved large storage capacity in the bleach liquor plant but extreme precaution is necessary in the decantation operation, and, no matter how carefully the decantation is made, or how long the period of settling, a certain percentage of finely divided lime always remains in suspension in the bleach liquor. In some cases even filtration of the bleach liquor has been resorted to for effecting separation of finely divided suspended lime. A part of the lime present is in a very fine state of sub-division and it is particularly this very finely divided material which will not settle out readily that causes trouble, both in removal and in subsequent use of the bleach liquor if it is not removed.

According to the present invention, the bleach liquor is clarified by chlorinating the remaining finely divided suspended lime

after an initial separation of the coarse suspended material without carrying the chlorination beyond neutrality. A clear stable bleach liquor, free from undissolved free lime, can thus be produced, while the long periods of settling and large storage capacity and the extreme precaution in decantation or the filtration hitherto required are eliminated. The method of the invention is applicable to bleach liquors prepared either by solution of bleaching powder or by chlorination of lime suspensions, but it is particularly effective in the clarification of chlorinated suspensions containing an excess of lime.

In carrying out the invention, the bleach liquor may be initially prepared in the customary way and in the concentrations commonly used. After initial preparation of the bleach liquor, for example, either by dissolving bleaching powder in water or by chlorinating an aqueous suspension of lime, e. g. milk of lime, it may be settled for a relatively short period and the coarse suspended matter so precipitated then separated from the liquor. While the very finely divided suspended lime requires a very long if not an indefinite period to settle, the coarse particles of suspended material settle comparatively rapidly and only a comparatively brief period is required, for example, the period of settling may be reduced to one-half or less of that now commonly employed. Following the separation of coarse suspended particles the partially clarified liquor is removed, as by decantation. The extreme precaution hitherto required in such operations may also be relaxed here because of the subsequent chlorination operation. The partially clarified bleach liquor then contains in suspension the finely divided lime particles which will not settle out readily.

The bleach liquor, which is then turbid due to free undissolved lime in suspension, is then chlorinated until the remaining lime in suspension goes into solution. The very finely divided lime difficult if not impossible to remove completely by the methods hitherto employed, is thus dissolved by the chlorination operation without the necessity of prolonged settling and careful decantation or filtration while the coarser suspended material which settles rapidly is removed by the preliminary operation. Any failure to

effect a complete separation of the coarse material in the initial clarification is also corrected by the chlorination operation. The chlorination is not carried beyond neutrality.

6 A clarified stable bleach liquor free from undissolved free lime is thus produced.

It will thus be seen that the present invention provides an improved method for eliminating free undissolved lime from 10 bleach liquor, and consequently of overcoming the difficulties encountered in the application of such bleach liquors in the pulp and paper industry. The invention effects a substantial saving in time and also reduces the 15 storage capacity required in any given instance. Conversely, the invention substantially increases the capacity of any existing bleach liquor plant. The time required and the storage capacity required may 20 be reduced as much as 50% or more. The invention also enables the production of bleach liquor free from suspended free lime to a degree hitherto approached only by filtration methods but without 25 requiring the carrying out of such operations. The process of the invention, moreover, may be carried out in existing bleach liquor plants without substantial modifica-

tion. It will be apparent that the invention is of more or less general application to the 30 clarification of bleach liquors where the elimination of free undissolved lime is desirable.

I claim:

1. An improved method of clarifying calcium hypochlorite bleach liquors containing suspended mineral matter including lime, which comprises separating from the bleach liquor coarse particles of suspended mineral matter and subsequently chlorinating the 40 separated liquor until the remaining finely divided suspended lime dissolves, without carrying the chlorination beyond neutrality.

2. An improved method of preparing bleach liquors, which comprises chlorinating 45 an aqueous suspension containing an excess of lime, separating from the chlorinated liquor coarse particles of suspended mineral matter, and subsequently further chlorinating the separated liquor until the remaining 50 finely divided suspended lime dissolves, without carrying the chlorination beyond neutrality.

In testimony whereof I affix my signature.

JAMES DOUGLAS MacMAHON.
